[57] ABSTRACT

Sheet handling apparatus is provided which includes structure for feeding a sheet in a predetermined path of travel, for sensing the sheet in the path of travel and providing at least one sensing signal indicative thereof, for printing postage indicia on the sheet, and for controlling the printing structure. The sensing structure is coupled to the controlling structure, which includes a microcomputer adapted to be energized from a local source of supply of power. The microcomputer is responsive to the at least one sensing signal for providing a time delay before commencement of operation of the printing structure to cause the postage indicia to be printed on the sheet a predetermined marginal distance from a reference edge of the sheet. The controlling structure includes a keyboard coupled to the microcomputer. The keyboard includes at least one key selectively operable for generating at least one key signal representative of a desired change in the marginal distance. The microcomputer is responsive to the key signal for providing an adjusted time delay before commencement of operation of the printing structure to cause the postage indicia to be printed on the sheet a changed marginal distance from the reference edge of the sheet, the changed marginal distance being the predetermined distance by the desired change in marginal distance. And the microcomputer includes a nonvolatile memory for storing therein an amount representative of the desired change in marginal distance.

SHEET HANDLING APPARATUS

BACKGROUND OF THE INVENTION

The present invention is generally concerned with sheet handling apparatus, and more particularly with apparatus for controlling the printing means in the combination of sheet feeding means and a postage meter wherein the postage meter includes a rotary sheet feeding and printing drum.

In U.S. patent application Ser. No. 657,546 for a Microprocessor Controlled D.C. Motor For Controlling Printing Means, filed by W. Kirshner and E. Salazar, Oct. 4, 1984, and assigned to the assignee of the present invention, there is described a postage meter which includes a rotary sheet feeding and printing drum coupled to a D.C. motor which is controlled by a microprocessor programmed for causing the drum to print indicia on mailpieces fed to the drum. The indicia is printed on each mailpiece a fixed, predetermined, distance from the leading edge of each mailpiece, independently of variations in the velocity of the respective mailpieces. In particular, drum rotation from a home position is commenced after a predetermined time delay which is adjusted with the velocity of the respective mailpieces fed to the drum, in order to provide for uniform spacing of the indicia from the leading edges of the respective mailpieces, as the drum is cyclically rotated for printing the indicia on each mailpiece while feeding the same downstream beneath the drum as the drum returns to its home position.

It has been found that slight variations occur in the marginal spacing of the indicia from the leading edges of successively fed mailpieces, although the velocity of the mailpieces remains constant, primarily due to the mailpieces having different thicknesses. In order to compensate for such variations in marginal spacing, it is desirable that the customer be provided with the capability of adjusting the marginal spacing of the indicia from mailpiece to mailpiece. In addition, it is desirable to provide the customer with this capability to allow for varying the margin on bordered mailpieces or in instances when the indicia is a slogan rather than postage or some other unit value, alone or in combination with a slogan. Further, it is preferable to provide this capability while at the same time compensating for deviations in the marginal spacing which would otherwise accompany different mailpiece velocities.

Accordingly, an object of the invention is to provide apparatus for controlling printing means;

Another object is to provide, in combination with means for printing indicia on a sheet, and microcomputer means for controlling the indicia printing means to cause the indicia to be printed a predetermined distance from an edge of the sheet, an improvement for changing the marginal distance;

Another object is to provide, in combination with means for printing indicia and means for feeding sheets to the printing means, apparatus for controlling the location of printing the indicia on respective sheets fed to the printing means;

Another object is to provide, sheet handling apparatus including means for feeding a sheet, means for printing postage indicia on the sheet, and operator-controlled means for controlling the marginal distance from the leading edge of the sheet that the postage indicia is printed on the sheet; and

Another object is to provide, in combination with a mailing machine and a postage meter, wherein the mailing machine includes sheet feeding means, the postage meter includes a rotary sheet feeding and indicia printing drum, and the mailing machine includes a D.C. motor coupled to the drum and controlled by a microcomputer, an improvement for controlling the location of printing the indicia on respective sheets fed to the drum.

10

SUMMARY OF THE INVENTION

Sheet handling apparatus is provided which comprises: means for feeding a sheet in a predetermined path of travel, the sheet having a reference edge, means for sensing the sheet in the path of travel and providing at least one sensing signal indicative thereof, means for printing postage indicia on the sheet, and means for controlling the printing means. The sensing means is coupled to the controlling means, which includes microcomputer means adapted to be energized from a local source of supply of power. The microcomputer means includes means responsive to said at least one sensing signal for providing a time delay before commencement of operation of the printing means to cause the postage indicia to be printed on the sheet a predetermined marginal distance from the reference edge of the sheet. The controlling means also includes keyboard means coupled to the microcomputer means. The keyboard means includes at least one key selectively operable for generating at least one key signal representative of a desired change in the marginal distance. The microcomputer means includes means responsive to said key signal for providing an adjusted time delay before commencement of operation of the printing means to cause the postage indicia to be printed on the sheet a changed marginal distance from the reference edge of the sheet, the changed marginal distance including the predetermined distance changed by the desired change in the marginal distance. And the microcomputer means includes nonvolatile memory means for storing therein an amount representative of the desired change in marginal distance.

BRIEF DESCRIPTION OF THE DRAWINGS

As shown in the drawings wherein like reference numerals designate like or corresponding parts throughout the several views:

FIG. 1 is a schematic view of a postage meter mounted on mailing machine according to the invention;

FIG. 2 is a schematic view of the mailing machine of FIG. 1, showing the operator control keys for changing the marginal spacing of indicia printing;

FIG. 3 shows the relationship between the position of a sheet and the periphery of the postage meter drum as a function of time, and an ideal velocity versus time profile of the periphery of the drum;

FIG. 4 is a perspective view of the quadrature encoder mounted on a D.C. motor drive shaft;

FIG. 5 shows the output signals from the quadrature encoder of FIG. 4 for clockwise and counter-clockwise rotation of the D.C. motor drive shaft;

FIG. 6 is a schematic diagram of a preferred counting circuit for providing an eight bit wide digital signal for the computer which numerically represents the direction of rotation, and angular displacement, of the motor drive shaft, and thus the drum, from its home position;

65

FIG. 7 shows a power amplifier circuit for coupling the computer to the D.C. motor.

FIG. 8 is a truth table showing the status of the transistors in the power amplifying circuit for clockwise and counter-clockwise rotation of the D.C. motor;

FIG. 9 shows the relationship between the encoder output signals for various D.C. motor duty cycles;

FIG. 10 shows a closed-loop servo system including the D.C. motor and computer;

FIG. 11 is a block diagram portraying the Laplace transform equations of the closed-loop servo system shown in FIG. 10;

FIG. 12 shows the equations for calculating the overall gain of the closed loop servo system of FIG. 10 before (FIG. 12a) and after (FIG. 12b) including a gain factor corresponding to the system friction at motor start up;

FIG. 13 is a bode diagram including plots for the closed loop servo system before and after compensation to provide for system stability and maximization of the system's bandwidth;

FIG. 14 shows the equation for calculating, in the frequency domain, the value of the system compensator;

FIG. 15 shows the equation for calculating the damping factor, overshoot and settling time of the servo controlled system;

FIG. 16 shows the equation for the Laplace operator expressed in terms of the Z-transform operator;

FIG. 17 shows the equation for calculating the value of the system compensator in the position domain;

FIG. 18 shows the equations for converting the system compensator of FIG. 17 to the position domain;

FIG. 19 shows the equation of the output of the system compensator in the time domain;

FIG. 20 is a block diagram of a preferred microprocessor for use in controlling the D.C. Motor;

FIG. 21 (including FIGS. 21a, 21b and 21c) shows the time intervals during which the motor control signal and its separable components are calculated to permit early application of the signal to the motor;

FIG. 22 (including FIGS. 22a, 22a- 1 and 22b) is a schematic diagram of the computer according to the invention; and

FIG. 23 (including FIGS. 23a- 1, 23a- 2, 23b and 23c) shows the flow charts portraying the processing steps of the computer.

DESCRIPTION OF THE PREFERRED EMBODIMENTS

As shown in FIG. 1, the apparatus in which the invention may be incorporated generally includes an electronic postage meter 10 which is suitably removably mounted on a conventional mailing machine 12, so as to form therewith a slot 14 (FIG. 2) through which sheets, including mailpieces 16, such as envelopes, cards or other sheet-like materials, may be fed in a downstream path of travel 18.

The postage meter 10 (FIG. 1) includes a keyboard 30 and display 32. The keyboard 30 includes a plurality of numeric keys, labeled 0-9 inclusive, a clear key, labeled "c" and a decimal point key, labeled ".", for selecting postage values to be entered; a set postage key, labeled "s", for entering selected postage values; and an arithmetic function key, labeled "±", for adding subsequently selected charges (such as special delivery costs) to a previously selected postage value before entry of the total value. In addition, there is provided a plurality

of display keys, designated 34, each of which are provided with labels well known in the art for identifying information stored in the meter 10, and shown on the display 32 in response to depression of the particular key 34, such as the "postage used", "postage unused", "control sum", "piece count", "batch value" and "batch count" values. A more detailed description of the keys of the keyboard 30 and the display 32, and their respective functions may be found in U.S. Pat. No. 4,283,721 issued Aug. 11, 1981 to Eckert, et al. and assigned to the assignee of the present invention.

In addition, the meter 10 (FIG. 1) includes a casing 36, on which the keyboard 30 and display 32 are conventionally mounted, and which is adapted by well known means for carrying a cyclically operable, rotary, postage printing drum 38. The drum 38 (FIG. 2) is conventionally constructed and arranged for feeding the respective mailpieces 16 in the path of travel 18, which extends beneath the drum 38, and for printing entered postage on the upwardly disposed surface of each mailpiece 16. For postage value selecting purposes, the meter 10 (FIG. 1) also includes a conventional postage value selection mechanism 40, for example, of the type shown in U.S. Pat. No. 4,287,825 issued Sept. 8, 1981 to Eckert, et al. and assigned to the assignee of the present invention. The mechanism 40 which is operably electrically coupled via the postage meter's computer 41 to the keyboard 30 and display 32, includes a first stepper motor 42 for selecting any one of a plurality of racks 43, associated on a one for one basis with each of the print wheels 44, and a second stepper motor 45 for actuating each selected rack 43 for positioning the appropriate printing element of the associated print wheel 44 at the outer periphery of the drum 38 for printing purposes. The rack selection stepper motor 42, which is referred to by skilled artisans as a bank selector motor, is appropriately energized via power lines 46 from the computer 41 for selecting the appropriate rack; and the rack actuating stepper motor 45, which is referred to by skilled artisans as a digit selector motor, is appropriately energized via power lines 47 from the computer 41 to move the selected rack for selecting the appropriate digit element of the associated print wheel 44. A more detailed description of the value selection mechanism 40 may be found in the aforesaid U.S. Pat. No. 4,287,825.

The computer 41 for the postage meter 10 generally comprises a conventional, microcomputer system having a plurality of microcomputer modules including a control or keyboard and display module, 41a, an accounting module 41b and a printing module 41c. The control module 41a is both operably electrically connected to the accounting module 41b and adapted to be operably electrically connected to an external device via respective two-way serial communications channels, and the accounting module 41b is operably electrically connected to the printing module 41c via a corresponding two-way serial communication channel. In general, each of the modules 41a, 41b and 41c includes a dedicated microprocessor 41d, 41e or 41f, respectively, having a separately controlled clock and programs. And two-way communications are conducted via the respective serial communication channels utilizing the echoplex communication discipline, wherein communications are in the form of serially transmitted single byte header-only messages, consisting of ten bits including a start bit followed by an 8 bit byte which is in turn followed by a stop bit, or in the form of a multi-

byte message consisting of a header and one or more additional bytes of information. Further, all transmitted messages are followed by a no error pulse if the message was received error free. In operation, each of the modules 41a, 41b and 41c is capable of processing data independently and asynchronously of the other. In addition, to allow for compatibility between the postage meter 10 and any external apparatus, all operational data transmitted to, from and between each of the three modules 41a, 41b and 41c, and all stored operational information, is accessible to the external device via the two-way communication channel, as a result of which the external apparatus (if any) may be adapted to have complete control of the postage meter 10 as well as access to all current operational information in the postage meter 10. In addition, the flow of messages to, from and between the three internal modules 41a, 41b and 41c is in a predetermined, hierarchical direction. For example, any command message from the control module 41a is communicated to the accounting module 41b, where it is processed either for local action in the accounting module 41b and/or as a command message for the printing module 41c. On the other hand, any message from the printing module 41c is communicated to the accounting module 41b where it is either used as internal information or merged with additional data and communicated to the control module 41c. And, any message from the accounting module 41b is initially directed to the printing module 41c or to the control module 41a. A more detailed description of the various prior art modules 41a, 41b and 41c, and various modifications thereof, may be found in U.S. Pat. Nos. 4,280,180; 4,280,179; 4,283,721 and 4,301,507, each of which patents is assigned to the assignee of the present invention.

The mailing machine 12 (FIG. 2), which has a casing 19, includes a A.C. power supply 20 which is adapted by means of a power line 22 to be connected to a local source of supply of A.C. power via a normally open main power switch 24 which may be closed by the operator. Upon such closure, the mailing machine's D.C. power supply 26 is energized via the power line 28. In addition, the mailing machine 12 includes a conventional belt-type conveyor 49, driven by an A.C. motor 50, which is connected for energization from the A.C. power supply 20 via a conventional, normally open solid state, A.C. motor, relay 52, which is timely energized by a computer 500 for closing the relay 52. Upon such closure the A.C. motor 50 drives the conveyor 49 for feeding mailpieces 16 to the drum 38. To facilitate operator control of the switch 24, the mailing machine preferably includes a keyboard 53 having a "start" key 53a and a "stop" key 53b, which are conventionally coupled to the main power switch 24 to permit the operator to selectively close and open the switch 24. Assuming the computer 500 has timely energized the relay 52, the A.C. motor 50 is energized from the A.C. power supply 20. Whereupon the conveyor 49 transports the individual mailpieces 16, at a velocity corresponding to the angular velocity of the motor 50, in the path of travel 18 to the postage printing platen 54.

The mailing machine 12 additionally includes first and second sensing devices respectively designated 56 and 58, which are spaced apart from each other a predetermined distance d_1 , i.e., the distance between points A and B in the path of travel 18. Preferably, each of the sensing devices 56 and 58, is an electro-optical device which is suitably electrically coupled to the computer 500; sensing device 56 being connected via communica-

tion line 60 and sensing device 58 being connected via communication line 62. The sensing devices 56, 58 respectively respond to the arrival of a mailpiece 16 at points A and B by providing a signal to the computer 500 on communication line 60 from sensing device 56 and on communication line 62 from sensing device 58. Thus, the rate of movement or velocity V_1 of any mailpiece 16 may be calculated by counting the elapsed time t_v (FIG. 3) between arrivals of the mailpiece 16 at points A and B, and dividing the distance d_1 , by the elapsed time t_v . Since the distance d_1 , is a mechanical constant of the mailing machine 12, the velocity of the mailpiece may be expressed in terms of the total number N_v of time instants T_v which elapse as the given mailpiece traverses the distance d_1 . For example, assuming a maximum velocity of 61 inches per second, $d_1=2.75$ inches and $T=1$ millisecond; the total number N_v of elapsed time instants T_v may be found by dividing $d_1=2.75$ inches by $V_1=61$ inches per second to obtain $N_v=45$, i.e., the total number of time instants T_v which elapse between arrivals of the mailpiece at points A and B. Thus, the number $N_v=45$ corresponds to and is representative of a mailpiece velocity of $V_1=61$ inches per second.

Assuming normal operation of the transport system and calculation of the value of V_1 having been made, the time delay t_d (FIG. 3a) before arrival of the mailpiece 16 at point C may be calculated by dividing the distance d_2 between points B and C by the mailpiece's velocity V_1 , provided the distance d_2 is known. Since the integral of the initial, triangularly-shaped, portion of the velocity versus time profile is equal to one-half of the value of the product of T_a and V_1 , and is equal to the arc d_3 described by point E on the drum 38, as the drum 38 is rotated counter-clockwise to point D, the distance between points C and D is equal to twice the arcuate distance d_3 . Accordingly, d_2 may be conventionally calculated, as may be the time delay t_d for the maximum throughput velocity. Assuming rotation of the drum 38 is commenced at the end of the time delay t_d and the drum 38 is linearly accelerated to the velocity V_1 to match that of the mailpiece 16 in the time interval T_a during which point E on the drum 38 arcuately traverses the distance d_3 to point D, T_a may be conventionally calculated. In addition, assuming commencement of rotation at the end of the time delay t_d and that the drum 38 is linearly accelerated to the velocity V_1 during the time interval T_a , the mailpiece 16 will arrive at point D coincident with the rotation of point E of the outer periphery 73 of the drum 38 to point D, with the result that the leading edge 73a of the drum's outer periphery 73, which edge 73a extends transverse to the path of travel 18 of the mailpiece 16, will engage substantially the leading edge of the mailpiece 16 for feeding purposes and the indicia printing portion 73b of the periphery 73 will be marginally spaced from the leading edge of the mailpiece 16 by a predetermined distance d_4 , i.e., the circumferential distance between points E and F on the drum 38. Since the circumferential distance d_5 on the drum 38 between points E and G is fixed, the time interval T_c during which the drum 38 is rotated at the constant velocity V_1 may also be calculated. When point G on the drum 38 is rotated out of engagement with the mailpiece 16, the drum 38 commences deceleration and continues to decelerate to rest during the time interval T_d . The distance d_6 which is traversed by point G, as the drum 38 is rotated to return point E to its original position of being spaced a distance d_3 from point D, is fixed, and, T_d may be chosen to provide a

suitable deceleration rate for the drum, preferably less than T_a . In addition, a reasonable settling time interval T_s is preferably added to obtain the overall cycling time T_{ct} of the drum 38 to allow for damping any overshoot of the drum 38 before commencing the next drum cycle. For a typical maximum drum cycle time period T_{ct} of 234 milliseconds and a maximum mailpiece transport rate of 61 inches per second, typical values for the acceleration, constant velocity, deceleration and settling time intervals are $T_a=37$ milliseconds, $T_c=124$ milliseconds, $T_d=24$ milliseconds and $T_s=234-185=49$ milliseconds. Utilizing these values, the required acceleration and deceleration values for the drum 38 during the time intervals T_a and T_d may be conventionally calculated. In addition, since the integral of the velocity versus time profile is equal to the distance traversed by the circumference of the drum 38 during a single revolution of the drum 38, the desired position of the drum 38 at the end of any sampling time period of $T=1$ millisecond may be calculated. For target velocities V_1 which are less than the maximum throughput velocity, it is preferably assumed that integral of, and thus the area under, the velocity versus time profile remains constant, and equal to the area thereof at the maximum throughput velocity, to facilitate conventional calculation of the values of the time delay t_d , the time intervals T_a , T_c and T_d , and the acceleration and deceleration values for each of such lesser velocities V_1 .

For computer implementation of the foregoing calculations, the computer 500 is programmed to continuously poll the communication lines 60 and 62, from the sensing devices 56 and 58, respectively, each time instant T_n at the end of each predetermined time period T , preferably $T=1$ millisecond, and to count the number of time instants T_n which elapse between arrivals of the mailpiece 16 at points A and B as evidenced by a transition signals on lines 60 or 62. Further, the computer 500 is programmed to calculate the current velocity of the mailpiece 16 in terms of the total number N , of the counted time intervals T_n , store the current velocity and, preferably, take an average of that velocity and at least the next previously calculated velocity (if any) to establish the target velocity V_1 . In addition, it is preferable that precalculated values for the time delay t_d , acceleration and deceleration corresponding to each of a plurality of target velocities be stored in the memory of the computer 500 for fetching as needed after calculation of the particular target velocity. For marginally spacing the indicia a different predetermined distance from the leading edge of the sheet then would be provided due to the drum's periphery initially engaging the leading edge of the sheet, the value of t_d may be altered at the time of programming the computer to cause the indicia to initially engage the sheet a different predetermined marginal distance from the leading edge of the sheet. The velocity at any time "t" of the drum 38 may be expressed by adding to the original velocity V_0 each successive increment of the product of the acceleration and time during each time period of $T=1$ millisecond, each successive increment of constant velocity and each successive increment of the product of the deceleration and time during each time period T . Preferably, the acceleration and deceleration values are each stored in the form of an amount corresponding to a predetermined number of counts per millisecond square which are a function of the actual acceleration or deceleration value, as the case may be, and of the scale factor herein-after discussed in connection with measuring the actual

angular displacement of the motor drive shaft 122; whereby the computer 500 may timely calculate the desired angular displacement of the motor drive shaft 122 during any sampling time interval T . In this connection it is noted that the summation of all such counts is representative of the desired linear displacement of the circumference of the drum 38, and thus of the desired velocity versus time profile of drum rotation for timely accelerating the drum 38 to the target velocity V_1 , maintaining the drum velocity at V_1 for feeding the particular mailpiece 16 and timely decelerating the drum 38 to rest.

According to the invention, independently of programming the computer 500 for providing for printing the indicia a predetermined marginal distance from the leading edge of each mailpiece 16, it is desirable that the operator of the mailing machine 12 (FIG. 2) be provided with the means for controlling the marginal distance. To that end, the keyboard 53 is provided with margin control keys 53c and 53d, which are respectively labeled "M.Incr." and "M.Decr." The keys 53c and 53d are conventionally coupled to the computer 500 for providing a signal to the computer 500 with each depression of the respective keys 53c and 53d. Preferably, each signal is representative of a predetermined increment of increase or decrease in the aforesaid predetermined marginal distance that the indicia printing portion 73b of the drum 38 is to be spaced from the leading edge of the mailpiece 16 upon engagement with the mailpiece 16. Thus, depression of the M.Incr. key 53c provides a signal representative of an increment of increase, whereas depression of the M.Decr. key 53d provides a signal representative of an increment of decrease, in the predetermined marginal distance, that the indicia will be spaced from the leading edge of the mailpiece 16 when printed. Accordingly, operator control is provided for changing the predetermined location of the indicia to a location which is closer to, or farther from, the leading edge of respective mailpieces, depending upon which of the keys 53c or 53d and the number of times each key 53c or 53d is depressed by the operator. For implementation purposes, the computer 500 is preferably programmed to provide an up count representative of each depression of the M.Incr. key 53c, and to provide a down count representative of each depression of the M.Decr. key 53d. The resulting count summation "n" of the up and down counts is then multiplied by an amount representative of a predetermined increment of distance "d," to obtain a total desired marginal distance change of d_{in} . As shown in FIG. 3(b) assuming the time delay t_d before commencing drum rotation is incrementally decreased, the entire drum cycle time period T_{ct} will be advanced by an incremental time interval of t_i . Since the velocity V_1 of the mailpiece 16 is unchanged, the mailpiece 16 will arrive at point D at the same time. However, the drum 38 will have commenced rotation earlier, with the result that the indicia printing portion 73b of the drum 38 will be marginally spaced a lesser distance, i.e., the product of t_i and the calculated target velocity of V_1 , from the leading edge of the mailpiece 16, when it engages the mailpiece 16 than it would have been had the time delay t_d not been incrementally decreased. Correspondingly, as shown in FIG. 3(c) incrementally increasing the time delay t_d by a time interval of t_i causes the drum cycle time period T_{ct} to be incrementally delayed and the drum 38 to commence rotation later; resulting in the indicia printing portion 73b being marginally spaced a

greater distance from the mailpiece's leading edge, when it engages the mailpiece 16, than it would have been had the time delay t_d not been incrementally increased. As shown in FIG. 3(a) the time period t_{bd} for a given mailpiece 16 to traverse the distance from point B to point D may be calculated for any mailpiece 16 by dividing the calculated target velocity $V1$ by the sum of the distances d_2 and $2 \times d_3$. Accordingly, for margin control purposes the print delay time period t_{pd} [FIGS. 3b and 3(c)] may be calculated for any given mailpiece 16 from the expression $t_{pd} = t_{bd} - T_a - (\pm t_i)$; wherein $t_i = d_{in}/V1$, $V1$ = the calculated target velocity of the mailpiece 16 and d_{in} is the summation n of the up and down count multiplied by a predetermined increment of distance d_i which is fetched as needed from the memory of computer 500. Thus the computer 500 may be conventionally programmed to change the marginal spacing that the indicia printing portion 73b of the drum 38 initially engages a given mailpiece 16, to change the location of the printed indicia from a reference edge of the mailpiece 16. The operator input signals from the keyboard are conventionally processed by the computer 500 for changing the marginal spacing of indicia printing, from the predetermined distance fixed by the fetched value of t_d for a given calculated mailpiece velocity $V1$, to a changed distance determined by the calculated value of t_{pd} , which, as hereinbefore discussed, is a function of the summation n of the up and down counts generated in response to the operator's successive depressions of the respective M.Incr. and M.decr. keys 53c and 53d. In practice, the count summation n may be altered by the operator from time to time during any given operating time interval of the mailing machine 12, i.e., from the time of depression of the start key 53a to time of subsequent depression of the stop key 53b. The current count summation is stored in an available working buffer of the computer 500 for fetching as needed to calculate during the operating time interval. Further, the current count summation n is preferably additionally stored in an available buffer of the non-volatile memory (NVM) of the computer 500 to avoid loss of the count summation n due to inadvertent deenergization of the computer 500 or due to ending the operating time interval, i.e., depressing the stop key 53b. Accordingly, at the commencement of the first operating time interval, i.e., when the start key 53a is first depressed, and until one of the keys 53c or 53d is depressed, the marginal distance that the printed indicia will be spaced from the leading edge of any mailpiece 16 will be the predetermined design distance for which various velocity dependent values of t_d are stored in the computer 500, and fetched as needed in response to changes in mailpiece velocity $V1$ for timely commencing rotation of the drum to provide printing indicia on a sheet a predetermined design, distance from the sheet's leading edge. Thereafter, with each depression of the respective keys 53c or 53d, the marginal distance will be changed to the distance determined by calculating the value of t_{pd} , whether or not the computer 500 is inadvertently deenergized or the stop key 53d is depressed to end the operating time interval. Preferably, the current count summation n is always stored in the non-volatile memory (NVM) or the computer 500 and copied into a working buffer of the computer 500 upon energization thereof, for fetching as needed from the working buffer for calculating the then current value of t_{dy} .

The postage meter 10 (FIG. 1) additionally includes a conventional, rotatably mounted, shaft 74 on which the drum 38 is fixedly mounted, and a conventional drive gear 76, which is fixedly attached to the shaft 74 for rotation of the shaft 74.

Further, the mailing machine 12 (FIG. 1) includes an idler shaft 80 which is conventionally journaled to the casing 19 for rotation, and, operably coupled to the shaft 80, a conventional home position encoder 82. The encoder 82 includes a conventional circularly-shaped disc 84, which is fixedly attached to the shaft 80 for rotation therewith, and an optical sensing device 86, which is operably coupled to the disc 84 for detecting an opening 88 formed therein and, upon such detection, signalling the computer 500. The machine 12, also includes an idler gear 90 which is fixedly attached to the shaft 80 for rotation therewith. Further, the machine 12 includes a D.C. motor 120, which is suitably attached to the casing 19 and has a drive shaft 122. The machine 12 also includes a pinion gear 124, which is fixedly attached to the drive shaft 122 for rotation by the shaft 122. The gear 124 is disposed in driving engagement with the idler gear 90. Accordingly, rotation of the motor drive shaft 122 in a given direction, results in the same direction of rotation of the drum drive shaft 76 and thus the drum 38. Preferably, the pinion gear 124 has one-fifth the number of teeth as the drum drive gear 76, whereas the idler gear 90 and drum drive gear 76 each have the same number of teeth. With this arrangement, five complete revolutions of the motor drive shaft 122 effectuate one complete revolution of the drum 38, whereas each revolution of the gear 90 results in one revolution of the gear 76. Since there is a one-to-one relationship between revolutions, and thus incremental angular displacements, of the drum shaft 74 and idler shaft 90, the encoder disc 84 may be mounted on the idler shaft 90 such that the disc's opening 88 is aligned with the sensing device 86 when the drum 38 is disposed in its home position to provide for detection of the home position of the drum shaft 74, and thus a position of the drum shaft 74 from which incremental angular displacements may be counted.

For sensing actual incremental angular displacements of the motor drive shaft 122 (FIG. 1) from a home position, and thus incremental angular displacements of the drum 38 from its rest or home position as shown in FIG. 2, there is provided a quadrature encoder 126 (FIG. 1). The encoder 126 is preferably coupled to the motor drive shaft 122, rather than to the drum shaft 74, for providing higher mechanical stiffness between the armature of the d.c. motor 120 and the encoder 126 to avoid torsional resonance effects in the system. The encoder 126 includes a circularly-shaped disc 128, which is fixedly attached to the motor drive shaft 122 for operably connecting the encoder 126 to the motor 120. The disc 128 (FIG. 4) which is otherwise transparent to light, has a plurality of opaque lines 130 which are formed on the disc 128 at predetermined, equidistantly angularly-spaced, intervals along at least one of the disc's opposed major surfaces. Preferably the disc 128 includes one hundred and ninety-two lines 130 separated by a like number of transparent spaces 132. In addition, the encoder 126 includes an optical sensing device 134, which is conventionally attached to the casing 19 and disposed in operating relationship with respect to the disc 128, for serially detecting the presence of the respective opaque lines 130 as they successively pass two reference positions, for example, posi-

tions 136a and 136b, and for responding to such detection by providing two output signals, one on each of communications lines 136a and 136b, such as signal A (FIG. 5) on line 136a and signal B on line 136b. Since the disc 128 (FIG. 4) includes 192 lines 130 and the gear ratio of the drum drive gear 76 (FIG. 1) to the motor pinion gear 124 is five-to-one, nine hundred and sixty signals A and B (FIG. 5) are provided on each of the communications lines 136a and 136b during five revolutions of the motor drive shaft 122, and thus, during each cycle of rotation of the drum 38. Since the angular distance between successive lines 130 (Fig. 4) is a constant, the time interval between successive leading edges (FIG. 5) of each signal A and B is inversely proportional to the actual velocity of rotation of the motor drive shaft (FIG. 1) and thus of the drum 38. The encoder 126 is conventionally constructed and arranged such that the respective reference positions 136a and 136b (FIG. 4) are located with respect to the spacing between line 130 to provide signals A and B (FIG. 5) which are 90 electrical degrees out of phase. Accordingly, if signal A lags signal B by 90° (FIG. 5) the D.C. motor shaft 122 (FIG. 1), and thus the drum 38, is rotating clockwise, whereas if signal A leads signal B by 90° (FIG. 5) the shaft 122 and drum 38 are both rotating counter-clockwise. Accordingly, the angular displacement in either direction of rotation of the drum 38 (FIG. 1) from its home position may be incrementally counted by counting the number of pulses A or B, (FIG. 5) as the case may be, and accounting for the lagging or leading relationship of pulse A (FIG. 5) with respect to pulse B.

The quadrature encoder communication lines, 136a and 136b (FIG. 1), may be connected either directly to the computer 500 for pulse counting thereby or to the computer 500 via a conventional counting circuit 270 (FIG. 6), depending on whether or not the internal counting circuitry of the computer 500 is or is not available for such counting purposes in consideration of other design demands of the system in which the computer 500 is being used. Assuming connection to the computer 500 via a counting circuit 270, the aforesaid communications lines, 136a and 136b are preferably connected via terminals A and B, to the counting circuit 270.

In general, the counting circuit 270 (FIG. 6) utilizes the pulses A (FIG. 5) to generate a clock signal and apply the same to a conventional binary counter 274 (FIG. 6), and to generate an up or down count depending on the lagging or leading relationship of pulse A (FIG. 5) relative to pulse B and apply the up or down count to the binary counter 274 (FIG. 6) for counting thereby. More particularly, the pulses A and B (FIG. 5) which are applied to the counting circuit terminals A and B (FIG. 6) are respectively fed to Schmidt trigger inverters 276A and 276B. The output from the inverter 276A is fed directly to one input of an XOR gate 278 and additionally via an R-C delay circuit 280 and an inverter 282 to the other input of the XOR gate 278. The output pulses from the XOR gate 278, which acts as a pulse frequency doubler, are fed to a conventional one-shot multivibrator 284 which detects the trailing edge of each pulse from the XOR gate 278 and outputs a clock pulse to the clock input CK of the binary counter 274 for each detected trailing edge. The outputs from the Schmidt trigger inverters 276A and 276B are respectively fed to a second XOR gate 286 which outputs a low logic level signal (zero), or up-count, to the up-down pins U/D of the binary counter 274 for each

output pulse A (FIG. 5) which lags an output pulse B by 90 electrical degrees. On the other hand the XOR gate 286 (FIG. 6) outputs a high logic level (one) or down-count, to the up-down input pins of the binary counter 274 for each encoder output pulse A (FIG. 5) which leads an output pulse B by 90° electrical degrees. Accordingly, the XOR gate 286 (FIG. 6) provides an output signal for each increment of angular displacement of the encoded shaft 122 (FIG. 1) and identifies the direction, i.e., clockwise or counter-clockwise, of rotation of the encoded shaft 122. The binary counter 274 (FIG. 6) counts the up and down count signals from the XOR gate 286 whenever any clock signal is received from the multivibrator 284, and updates the binary output signal 272 to reflect the count.

Accordingly, the counting circuit 270 converts the digital signals A and B, which are representative of incremental angular displacements of the drive shaft 122 in either direction of rotation thereof, to an eight bit wide digital logic output signal 272 which corresponds to a summation count at any given time, of such displacements, multiplied by a factor of two, for use by the computer 500. Since the angular displacement of the shaft 122 from its home position is proportional to the angular displacement of the drum 38 from its home position, the output signal 272 is a count which is proportional to the actual linear displacement of the outermost periphery of the drum 38 at the end of a given time period of rotation of the drum 38 from its home position. For a typical postage meter drum 38, having a circumference, i.e., the arc described by the outermost periphery of the drum 38 in the course of revolution thereof, of 9.42 inches, which is connected to the motor drive shaft 122 via a mechanical transmission system having a 5:1 gear ratio between the motor 120 and drum 38, wherein the encoder disc 128 has 192 lines; the counting circuit 270 will provide an output of $2 \times 192 = 384$ counts per revolution of the shaft 122, and $5 \times 384 = 1920$ counts per revolution of the drum 38 which corresponds to 203.82 counts per inch of linear displacement of the periphery of the drum. Accordingly, the maximum mailpiece transport velocity of $V_1 = 61(10^{-3})$ inches per millisecond may be multiplied by a scale factor of 203.82 counts per inch to express the maximum transport velocity in terms of counts per millisecond, or, counts per sampling time period T where $T = 1$ millisecond; i.e., $61(10^{-3})$ inches per millisecond times 203.82 counts per inch = 12.43 counts per sampling time period T. Similarly, any other target velocity V_1 , or any acceleration or deceleration value, may be expressed in terms of counts per sampling time interval T, or counts per square millisecond, as the case may be, by utilization of the aforesaid scale factor.

For energizing the D.C. motor 120 (FIG. 1) there is provided a power amplifying circuit 300. The power amplifying circuit 300 (FIG. 7) is conventionally operably connected to the motor terminals 302 and 304 via power lines 306 and 308 respectively. The power amplifying circuit 300 preferably comprises a conventional, H-type, push-pull, control signal amplifier 301 having input leads A, B, C and D, a plurality of optical-electrical isolator circuits 303 which are connected on a one-for-one basis between the leads A-D and four output terminals of the computer 500 for coupling the control signals from the computer 500 to the input leads A, B, C, and D of the amplifier 301, and a plurality of conventional pull-up resistors 305 for coupling the respective leads A-D to the 5 volt source. The amplifier 301 in-

cludes four conventional darlington-type, pre-amplifier drive circuits including NPN transistors T1, T2, T3 and T4, and four, conventional, darlington-type power amplifier circuits including PNP transistors Q1, Q2, Q3 and Q4 which are respectively coupled on a one-for-one basis to the collectors of transistors T1, T2, T3 and T4 for driving thereby. The optical-electrical isolator circuits 303 each include a light emitting diode D1 and a photo-responsive transistor T5. The cathodes of D1 are each connected to the 5 volt source, the emitters of T5 are each connected to ground and the collectors of T5 are each coupled, on a one-for-one basis, to the base of one of the transistors T1, T2, T3 and T4. With respect to each of the opto-isolator circuits 303, when a low logic level signal is applied to the anode of D1, D1 conducts and illuminates the base of T5 thereby driving T5 into its conductive state; whereas when a high logic level signal is applied to the anode of D1, D1 is non-conductive, as a result of which T5 is in its non-conductive state. With respect to each of the combined amplifier circuits, T1 and Q1, T2 and Q2, T3 and Q3, and T4 and Q4, when the lead A, B, C or D, as the case may be, is not connected to ground via the collector-emitter circuit of the associated opto-isolator circuit's transistor T5, the base of T1, T2, T3 or T4, as the case may be, draws current from the 5 volt source via the associated pull-up resistor 305 to drive the transistor T1, T2, T3 or T4, as the case may be, into its conductive state. As a result, the base of transistor Q1, Q2, Q3 or Q4, as the case may be, is clamped to ground via the emitter-collector circuit of its associated driver transistor T1, T2, T3 or T4, thereby driving the transistor Q1, Q2, Q3 or Q4, as the case may be, into its conductive state. Contrariwise, the transistor pairs T1 and Q1, T2 and Q2, T3 and Q3, and T4 and Q4 are respectively biased to cut-off when lead A, B, C or D, as the case may be, is connected to ground via the collector-emitter circuit of the associated opto-isolator circuit's transistor T5. As shown in the truth table (FIG. 8) for clockwise motor rotation, Q1 and Q4 are turned on and Q2 and Q3 are turned off, whereas for counter-clockwise motor rotation, Q2 and Q3 are turned on and Q1 and Q4 are turned off. Accordingly, for clockwise motor rotation: terminal 302 (FIG. 7) of the motor 120 is connected to the 30 volt source via the emitter-collector circuit of Q1, which occurs when Q2 is turned off and the base of Q1 is grounded through the emitter-collector circuit of T1 due to the base of T1 drawing current from the 5 volt source in the presence of a high logic level control signal at input terminal A; and terminal 304 of the motor 120 is connected to ground via the emitter-collector circuit of Q4, which occurs when Q3 is turned off and the base of Q4 is grounded through the emitter-collector circuit of T4 due to the base of T4 drawing current from the 5 volt source in the presence of a high logic level signal at the input terminal D. On the other hand, for counter clockwise rotation of the motor 120: terminal 302 of the motor 120 is connected to ground via the emitter-collector circuit of Q2, which occurs when Q1 is turned off and the base of Q2 is grounded through the emitter-collector circuit of T2 due to the base of T2 drawing current from the 5 volt source in the presence of a high logic level control signal at the input terminal B; and terminal 304 of the motor 120 is connected to the 30 volt source via the emitter-collector circuit of Q3, which occurs when Q4 is turned off and the base of Q3 is grounded through the emitter-collector of T3 due to the base of T3 drawing current from the 5 volt source in

the presence of a high logic level control signal at the input terminal C. For turning off the respective powers transistors Q1-Q4, on a two at a time basis, low level control signals are applied on a selective basis to the two terminals B and C, or A and D, as the case may be, to which high logic control level signals are not being applied; which occurs when the opto-isolator circuit's transistors T5 associated with the respective leads B and C or A and D are driven to their conductive states. 5 When this occurs the bases of the transistors T2 and T3, or T1 and T4, as the case may be, are biased to open the emitter-collectors circuits of the transistors T2 and T3, or T1 and T4, as the case may be, as a result of which the bases of the transistors Q2 and Q3, or Q1 and Q4, as the case may be, are biased to open the emitter-collector circuits of transistors Q2 and Q3, or Q1 and Q4, as the case may be. 10 The velocity of the motor 120 (FIG. 7) is controlled by modulating the pulse width and thus the duty cycle 20 of the high logic level, constant frequency, control signals, i.e., pulse width modulated (PWM) signals, which are timely applied on a selective basis to two of the leads A-D, while applying the low level logic signals to those of leads A-D which are not selected. For example, assuming PWM signals (FIG. 9) having a 50% duty cycle are applied to leads A and D (FIG. 7), and low level logic signals are applied to leads B and C, for clockwise rotation of the motor 120, the velocity of the motor 120 will be greater than it would be if high logic level PWM signals (FIG. 9) having a 25% duty cycle were similarly applied and will be less than it would be if high logic level PWM signals having a 75% duty cycle were similarly applied. Accordingly, assuming rotation of the motor 120 (FIG. 7) is commenced by 30 utilizing high logic level PWM signals having a given duty cycle percentage, the velocity of the motor 120 may be decreased or increased, as the case may be, by respectively decreasing or increasing the duty cycle percentage of the applied high logic level PWM signals. 35 Further, assuming the motor 120 is rotating clockwise due to PWM signals having a selected positive average value being applied to leads A and D, in combination with low level logic signals being applied to leads B and C, the motor 120 may be dynamically braked by temporarily applying high level PWM signals having a selected duty cycle corresponding to a given positive average value to leads B and C, in combination with low logic signals being applied to leads A and D. To avoid damage to the power transistors Q1, Q2, Q3 and 40 Q4 which might otherwise result, for example, due to current spikes accompanying back emf surges which occur in the course of switching the circuit 301 from one mode of operation to the other, the emitter-collector circuits of the power transistors Q1, Q2, Q3 and Q4 are respectively shunted to the 30 volt source by appropriately poled diodes, D1, D2, D3 and D4 connected across the emitter-collector circuits of Q1, Q2, Q3 and Q4. 45 To control the motion of the drum 38 (FIG. 1) during each cycle of drum rotation, the D.C. motor 120 and its shaft encoder 126 are respectively connected to the computer 500 via the power amplifier circuit 300 and the counting circuit 270. And the computer 500 is programmed to calculate the duration of and timely apply PWM control signals to the power amplifier circuit 300 after each sampling time instant T_n , utilizing an algorithm based upon a digital compensator $D(s)$ derived from analysis of the motor 120, motor load 38, 74, 76, 90

and 124 amplifying circuit 300, encoder 126, counting circuit 270, and the digital compensator D(s) in the closedloop, sampled-data, servo-control system shown in FIG. 10.

With reference to FIG. 10, in general, at the end of each predetermined sampling time period of $T=1$ millisecond, the eight bit wide count representing the angular displacement of the motor drive shaft 122, and thus the drum 38, from its home position is sampled by the computer 500 at the time instant T_n . Under the control of the program of the computer 500 (FIG. 10), a summation is taken of the aforesaid actual count and the previously calculated count representing the desired position of the motor drive shaft 122, and thus the drum 38, at the end of the time period T , and, under control of the computer program implementation of the algorithm, a PWM control signal which is a function of the summation of the respective counts, or error, is applied to the power amplifier circuit 301 for rotating the motor drive shaft 122 such that the error tends to become zero at the end of the next sampling time period T .

To derive the algorithm, the servo-controlled system of FIG. 10 is preferably analyzed in consideration of its equivalent Laplace transformation equations shown in FIG. 11, which are expressed in terms of the following Table of Parameters and Table of Assumptions.

TABLE I

Parameter	Symbol	Value and/or Dimension
Zero-Order-Hold	ZOH	None
Laplace Operator	S	jw
Sampling Interval	T	Milliseconds
PWM D.C. Gain	K_v	Volts
PWM Pulse Amplitude	V_p	5 Volts
PWM Pulse Width	t_1	10^{-6} Microseconds
Power Switching Circuit Gain	K_a	None
Motor back e.m.f. Constant	K_e	0.63 Volts/radian/second
Motor Armature Resistance	R_a	1.65 Ohms
Motor Armature Moment of Inertia	J_a	$2.12 (10^{-5})$ kilograms (meters ²)
Motor Torque Constant	K_t	0.063 Newton-Meters/amp
Drum Moment of Inertia	J_1	$70.63 (10^{-5})$ kilograms (meters ²)
Gear Ratio, Motor to Load	G	5:1, None
Motor Armature Inductance	L_a	2.76 Millihenrys
Motor Shaft Encoder Gain	K_p	Counts/radian
Motor Shaft Encoder Constant	K_b	192 Lines/revolution
Counting Circuit Multiplier	K_x	2, None
Motor Gain	K_m	16, None
Poles in frequency domain	f_1, f_2	48, 733 Radians/second
Starting Torque Gain	K_c	None
System Overall Gain	K_o	None

TABLE II—ASSUMPTIONS

ZOH: Since the output and input are held constant during each sampling period a zero-order-hold is assumed to approximate the analog time function being sampled.

Veg.: Since the integral of the voltage in time is assumed equal to the area under the PWM pulse, the output from the PWM is linear.

With reference to FIG. 10, D(s) is the unknown transfer function of an open loop compensator in the frequency domain. Due to a key factor for providing acceptably fast motor response being the system's resonance between the motor and load, the derivation of the transfer function D(s) for stabilization of the system is

preferably considered with a view to maximizing the range of frequencies within which the system will be responsive, i.e., maximizing the system's bandwidth, BW. For calculation purposes a sampling period of $T=1$ millisecond was chosen, due to having chosen a Model 8051 microprocessor, available from Intel Corporation, Palo Alto Calif., for control purposes, and inasmuch as the Model 8051 microprocessor equipped with a 12 MHz crystal for providing a clock rate of 12 MHz, is able to conveniently implement a 1 KHz sampling rate and also implement application software routines, after control algorithm iterations, during the sampling period of $T=1$ millisecond. However, other sampling periods and other conventional microprocessors may be utilized without departing from the spirit and scope of the invention.

The open loop system gain $H_1(S)$ without compensation, of the servo-loop system of FIG. 10 is shown in FIG. 12(a). To tolerate inaccuracies in the transmission system between the motor and drum load, such as backlash, it was considered acceptable to maintain a steady-state count accuracy of plus or minus one count. To reflect this standard, the gain equation of FIG. 12(a) was adjusted to provide a corrective torque C_t with a motor shaft movement, in radians per count, equivalent to the inverse expressed in radians per count, of the gain K_p of the encoder counting circuit transform. Since the corrective torque C_t is primarily the friction of the transmission system which has to be overcome by the motor at start-up, the value of C_t may be assumed to be substantially equal to a maximum estimated numerical value based on actual measurements of the starting friction of the system, i.e., 35 ounce-inches, as a result of which a numerical value of the starting voltage V_s may be calculated from the expression $V_s=(C_t)R_a/K_t$, i.e., $V_s=6.5$ volts, which, in turn, permits calculation of a numerical value for the minimum overall system gain K_o , at start-up, from the equation $K_o=V_s/K_p$, i.e., $K_o=397$ volts per radian, or for simplication purposes, 400 volts/radian. Accordingly, the open-loop uncompensated gain $H_1(S)$ may be rewritten as $H_2(S)$ as shown in FIG. 12(b), in which a gain factor of K_c has been included, to account for the torque C_t and the value of K_o is substituted for the overall D.C. gain, i.e., $(K_v)(K_m)(K_p)(K_a)(K_c)=K_o$. Although the numerical value of K_c may also be calculated, it is premature to do so, since it has not as yet been established that K_o , which has been adjusted by the value of K_c to provide a minimum value of K_o , is acceptable for system stability and performance purposes. Otherwise stated, K_o may not be the overall system gain which is needed for system compensation for maximizing the system bandwidth BW, as a result of which it is premature to conclude that K_c will be equivalent to the D.C. gain of the system compensator D(S).

At this juncture, the Bode diagram shown in FIG. 13, may be constructed due to having calculated a minimum value for K_o . As shown in FIG. 13, the absolute value of $H_2(S)$, in decibels, has been plotted against the frequency W in radians per second, based on the calculated minimum value of K_o , the selected value of T and calculated values of the poles f_1 and f_2 . From the Bode diagram, a numerical value of the cross-over frequency W_{c1} of the Bode plot of $H_2(S)$ may be determined, i.e., W_{c1} was found to be substantially 135 radians per second. And, since the value of W_{c1} is substantially equal to the bandwidth BW_u of the uncompensated open-loop

system $H_2(S)$, a calculation may be made of the phase margin θ_m of the uncompensated system from the expression $\phi_m = 180^\circ - \theta$ [$H(S)$] at W_{c1} , or, otherwise stated: $\phi_m = 180^\circ - \tan^{-1}(W_{c1}/f_1) - \tan^{-1}(W_{c1}/f_1) - \tan^{-1}(W_{c1}/f_2) - \tan^{-1}(W_{c1}T/2)$. From this calculation, there was obtained a phase margin value which was much, much, less (i.e., 5°) than 45°, which, for the purposes of the calculations was taken to be a minimum desirable value for the phase margin ϕ_m in a position-type servo system. Accordingly, it was found that the uncompensated system $H_2(S)$ was unstable if not compensated. Since an increase in phase lead results in an increase in bandwidth BW, and the design criteria calls for maximizing the bandwidth BW and increasing the phase margin to at least 45°; phase lead compensation was utilized.

By definition, a phase lead compensator $D(S)$ has the Laplace transform shown in FIG. 14, wherein K_c is the phase lead D.C. gain, and f_z and f_p are respectively a zero frequency and a pole frequency. Adding the transfer function of the phase lead compensator $D(S)$ to the Bode plot of the uncompensated system's transfer function $H_2(S)$, results in the Bode plot of the compensated system transfer function $H_3(S)$, if the zero frequency f_z of the phase lead compensator $D(S)$ is chosen to be equivalent to f_1 in order to cancel the lag due to the mechanical time constant of the uncompensated transfer function $H_2(S)$. As shown in FIG. 13, the cross-over frequency W_{c2} for the compensated system $H_3(S)$ may be read from the Bode diagram, i.e., W_{c2} was found to be substantially equal to 400 radians per second. And, since by definition the crossover frequency W_{c2} lies at the geometric mean of f_p and f_z , the value of the f_p may be established by doubling, from f_z , the linear distance between W_{c2} and f_z , as measured along the logarithmic frequency axis, W , and reading the value of f_p from the Bode diagram, i.e., f_p was found to be substantially equal to 3,400 radians per second. Since numerical values may thus be assigned to both W_{c2} and f_p from the Bode diagram, the compensated phase margin ϕ_{mc} , i.e., the phase margin for the phase lead compensated system $H_3(S)$ in which f_z has been equated to f_1 , may be found from the expression $\phi_{mc} = 180^\circ - 90^\circ - \tan^{-1}(W_{c2}/f_2) - \tan^{-1}(W_{c2}T/2)$. Upon calculating the compensated phase margin ϕ_{mc} it was found to be 50° and, therefore, greater than the minimum phase margin criteria of 45°. In addition, the value of W_{c2} for the compensated system $H_3(S)$ was found to be substantially three times that of the uncompensated system $H_2(S)$, as a result of which the bandwidth BW of the system $H(S)$ was increased by a factor of substantially three to BW_c .

At this juncture, the compensated system $H_3(S)$ is preferably analyzed with reference to the system's overshoot O_s and settling time t_s based on a calculation of the system damping factor d_f and the assumption that the system will settle in five times constants, i.e., $t_s = 5t_x$. The relevant values may be calculated or estimated, as the case may be, from the expressions, for d_f , O_s , t_x and t_s shown in FIG. 15. In connection with this analysis, reference is also made to the typical mailing machines hereinbefore described, wherein a maximum drum cycle time period T_{ct} (FIG. 3) of 234 milliseconds and a maximum mailpiece transport speed (FIG. 2) of 61 inches per second are typical values. Assuming the velocity profile of FIG. 3, and, as previously discussed an acceleration time period of $T_a = 37$ milliseconds, a constant velocity time period of $T_c = 124$ milliseconds and deceleration time period of $T_d = 24$ milliseconds,

the longest permissible settling time for the system was calculated, i.e., $T_{ct} - (T_a + T_c + T_d) = 234 - 185 = 49$ milliseconds. For analysis purposes a series of calculations of the aforesaid system characteristics and phase margin were performed, assuming incremental increases in the overall system gain K_o , while holding $f_z = f_1$. The results of such calculations are shown in the following Table III.

TABLE III

K_o = system gain	$H_3(S)$ with $f_z = f_1$		O_s = overshoot (percent)	t_s = settling time (MS.)
	$W_c = BW$ (rad./sec.)	θ_m = phase Margin (deg.)		
400	400	50	28	28.67
447	450	46	31	27.78
501	500	42	34	27.50
562	550	38	38	27.41

As shown in Table III, the system bandwidth BW may be maximized at 450 radians per second while maintaining a phase margin ϕ_m of at least 45° the two design criteria discussed above. Although this results in an increase in system overshoot O_s accompanied by a negligible decrease in the settling time t_s , the settling time t_s is well within the maximum allowable settling time, $T_s = 49$ milliseconds. On the other hand, if a bandwidth of 400 radians per second is acceptable, it is desirable to reduce the percentage of overshoot O_s , and increase the phase margin to $\phi_{mc} = 50$ to provide for greater system stability than would be available with a phase margin value (i.e., 46°) which is substantially equal to the design criteria minimum of 45°; in which instance it is preferable to choose the bandwidth of $BW = 400$ radians per second, overshoot of $O_s = 28\%$ and compensated phase margin of $\phi_{mc} = 50^\circ$. For the example given, a compensated Bandwidth of $BW_c = 400$ radians per second is acceptable inasmuch as worst case load conditions were assumed. In this connection it is noted that the foregoing analysis is based on controlling a postage meter drum, which has a high moment of inertia, contributes high system friction, and calls for a cyclical start-stop mode of operation during which the load follows a predetermined displacement versus time trajectory to accommodate the maximum mailpiece transport speed in a typical mailing machine. Accordingly, the compensated system bandwidth $BW_c = 400$ radians per second may be chosen, as a result of which the overall system gain K_o may be fixed at $K_o = 400$, and the value of K_c may be calculated from the expression $K_c = K_o / (K_v)(K_a)(K_p)$. Since $f_z = f_1$, and f_1 and f_p are also known, the Bode plot of the compensator $D(S)$, FIG. 14, may be added to the Bode diagram (FIG. 13) wherein the system compensator $D(S)$ is shown as a dashed line.

Since the analog compensator $D(S)$ was derived in the frequency domain, $D(S)$ was converted to its Z-transform equivalent $D(Z)$ in the sampled data domain for realization in the form of a numerical algorithm for implementation by a computer. Of the numerous well-known techniques for transforming a function in the frequency domain to a function in the sampled-data domain, the bi-linear transformation may be chosen. For bi-linear transformation purposes the Laplace operator S is defined by the expression shown in FIG. 16. Using the values $K_c = 13.64$, $f_z = f_1 = 48$, and $f_p = 3,400$ in the expression for $D(S)$ shown in FIG. 14, and substituting the bilinear transformation expression for S shown

in FIG. 16 and the sampling interval $T=1$ millisecond, in the expression shown in FIG. 14 results in the expression for $D(Z)$ shown in FIG. 17. As shown in FIG. 11, $D(T)=\text{output/input}=g(T)/e(T)$, which, in the sampled data domain is expressed by the equation $D(Z)=G(Z)/E(Z)$. Accordingly, the expression for $D(Z)$ shown in FIG. 17 may be rewritten as shown in FIG. 18a. Cross-multiplying the equivalency of FIG. 18a results in the expression shown in FIG. 18b, which defines the output $G(Z)$ in the sampled data domain of the system compensator $D(S)$. Taking the inverse Z -transform of the expression shown in FIG. 18b, results in the expression shown in FIG. 19 which defines the output $G(T_n)$ in the time domain of the system compensator $D(S)$, and is a numerical expression of the algorithm to be implemented by the computer for system compensation purposes. As shown by the expression in FIG. 19 and in the following Table IV the output of the digital compensator for any current sampling instant T_n is a function of the position error at the then current sampling time instant T_n , is a function of the position error at the end of the next previous sampling time instant T_{n-1} and is a function of the algorithm output at the end of the next previous sampling time instant T_{n-1} .

TABLE IV

Function	Definition
$G(T_n)$	Algorithm output for current sampling time instant T_n
$E(T_n)$	Position error for current sampling time instant T_n
$G(T_{n-1})$	Algorithm output for next previous sampling time instant T_{n-1}
$E(T_{n-1})$	Position error for next previous sampling time instant T_{n-1}
$K_1, K_2 & K_3$	Constants of the compensated system which are a function of the parameters of the motor load and system friction for a sampling time period of $T = 1$ millisecond.

Accordingly, the algorithm which is to be implemented by the computer 500 for system compensation purposes is a function of a plurality of historical increments of sampled data for computing an input value for controlling a load to follow a predetermined position trajectory in a closed loop sampled-data servo-control system.

As shown in FIG. 20 the computer 500 preferably includes a conventional, inexpensively commercially available, high speed microprocessor 502, such as the Model 8051 single chip microprocessor commercially available from Intel Corporation, 3065 Bowers Ave., Santa Clara, Calif. 95051. The microprocessor 502, generally comprises a plurality of discrete circuits, including those of a control processor unit or CPU 504, an oscillator and clock 506, a program memory 508, a data memory 510, timer and event counters 512, programmable serial ports 514, programmable I/O ports 516 and control circuits 518, which are respectively constructed and arranged by well known means for executing instructions from the program memory 508 that pertain to internal data, data from the clock 506, data memory 510, timer and event counter 512, serial ports 514, I/O ports 514 interrupts 520 and/or bus 522 and providing appropriate outputs from the clock 506, serial ports 514, I/O ports 516 and timer 512. A more detailed discussion of the internal structural and functional characteristics and features of the Model 8051 microprocessor, including optional methods of pro-

gramming port 3 for use as a conventional bidirectional port, may be found in the Intel Corporation publication entitled MCS-51 Family of Single Chip Microcomputers Users Manual, dated January 1981.

For implementing the sampling time period of $T=1$ millisecond, one of the microprocessor's timer and event counters 512 (FIG. 20) is conventionally programmed as a sampling time period clock source. To that end, a timer 512 is programmed for providing an interrupt signal each 250 microseconds, and each successive fourth interrupt signal is utilized as a clock signal for timing the commencement of successive sampling time periods of $T=1$ millisecond.

In general, as shown in FIG. 21, at the commencement of each sampling time period of $T=1$ millisecond, during the sampling instant T_n , a sample is taken of the count representative of the actual angular displacement of the motor drive shaft and, substantially immediately thereafter, the actual count is summed with the count representative of the desired angular displacement of the motor drive shaft which was calculated during the next preceding time period T in order to obtain the then current error value $E(T_n)$ for calculating the then current compensation algorithm output value $G(T_n)$. Due to the recursive mathematical expression for $G(T_n)$ [FIG. 19] being a function of the then current error value $E(T_n)$, the next previous error value $E(T_{n-1})$ and the next previous compensation algorithm output value $G(T_{n-1})$, the expression for $G(T_n)$ is preferably separated into two components for calculation purposes, i.e., $G(T_n)=g_1+g_2$; wherein $g_1=K_1 \times E(T_n)$, and wherein $g_2=-[K_2 \times E(T_{n-1})+K_3 \times G(T_{n-1})]$, to permit calculation of the value of g_2 in advance of the time period T when it is to be added to the value of g_1 for calculating the value of $G(T_n)$, thereby reducing to a negligible value (in view of the time period T) the time delay T_{dy} before completion of sampling the actual displacement of the motor drive shaft at the instant T_n and applying the PWM motor control signal to the output ports of the microprocessor. For example, when calculating the value of $G(T_n)$ based upon the first error value resulting from the summation of the counts representing the desired and actual angular displacements of the motor drive shaft, the value of g_2 is by definition equal to zero since the error signal $E(T_{n-1})$ is equal to zero, due to the desired and actual angular displacement values during the next previous sampling time period T having been equal to each other. Accordingly, upon obtaining the value of the first error signal $E_1(T_n)$, the value of $G_1(T_n)$ may be calculated as being equivalent to g_1 , i.e., $G_1(T_n)=g_1=K_1 \times E_1(T_n)$. And, upon calculating $G_1(T_n)$ the value of g_2 for use in calculating the next successive compensation algorithm output value $G(T_{n+1})$ may be calculated for subsequent use, since $g_2(T_{n+1})=-[K_2 \times E_1(T_n)+K_3 \times G_1(T_n)]$, and $K_2, K_3, E_1(T_n)$ and $G_1(T_n)$ are all known values. In addition, during any given time period T , a calculation may be made of the desired angular displacement of the motor drive shaft for the next subsequent time period T . Preferably, the microprocessor is programmed for implementation of the aforesaid calculation process to facilitate early utilization of the compensation algorithm output value $G(T_n)$ for driving the D.C. motor. Accordingly, the microprocessor is preferably programmed for: during the first sampling time period T_1 , sampling the count representative of the actual angular displacement of the motor drive shaft at the time instant T_n , then taking the summation of that count and the

previously calculated value of the desired angular displacement of the motor drive shaft to obtain the first error value $E_1(T_n)$, then calculating the first compensation algorithm output value $G_1(T_n) = K_1 \times E_1(T_n) + g_2$, wherein $g_2 = 0$, and generating a PWM motor control signal representative of $G_1(T_n)$, then calculating the value of g_2 for the next sampling time period, i.e., $g_2 = -[K_2 \times E_1(T_n) + K_3 \times G_1(T_n)]$, and then calculating the count representing the desired angular displacement of the motor drive shaft for use during the next sampling time period T_2 ; during the second sampling time period T_2 , sampling the count representative of the actual angular displacement of the motor drive shaft and taking the summation of that count and the previously calculated desired count to obtain the error value $E_2(T_{n+1})$, calculating the compensation algorithm output value $G_2(T_{n+1}) = K_1 \times E_2(T_{n+1}) + g_2 = K_1 \times E_2(T_{n+1}) - K_2 \times E_1(T_n) - K_3 \times G_1(T_n)$, and generating a PWM motor control signal representative thereof, then calculating the value of g_2 for the next sampling time period T_3 , i.e., $g_2 = -[K_2 \times E_2(T_{n+1}) + K_3 \times G_2(T_{n+1})]$, and then calculating the count representative of the desired angular displacement of the motor drive shaft for use during the time period T_3 ; and so on, during each successive sampling time period.

Accordingly, as shown in FIG. 21, the microprocessor is programmed for immediately after calculating the then current compensation algorithm output value $G(T_n)$, and thus while the calculation of the value of g_2 for the next sampling time period is in progress, generating a motor control signal for energizing the power amplifier. For this purpose, the relative voltage levels of motor control signal are determined by the sign, i.e., plus or minus, of the compensation algorithm output value $G(T_n)$, and the duty cycle of the control signal is determined by the absolute value of the compensation algorithm output value $G(T_n)$. Preferably, for timing the duration of the motor control signal, the other timer and event counter 512, i.e., the timer 512 which was not used as a sampling time period clock source, is utilized for timing the duration of the duty cycle of the motor control signal. For example, by loading the absolute value of the $G(T_n)$ into the other timer 512, commencing the count, and timely invoking an interrupt for terminating the duty cycle of the control signal. As shown in FIG. 21(c), the time delay T_{dy} from commencement of the time period T to updating the PWM motor control signal at the output ports of the microprocessor is substantially 55 microseconds, and the time interval allocated for calculating the value of g_2 and the count representative of the desired angular displacement of the motor drive shaft for use during the next time period is substantially 352 microseconds. As a result, substantially 593 microseconds of microprocessor calculation time is available during any given sampling time period $T=1$ millisecond for implementing non-motor control applications.

As shown in FIG. 22 the computer 500 is preferably modularly constructed for segregating the components of the logic circuit 501a and analog circuit 501b of the computer 500 from each other. To that end, the respective circuits 501a and 501b may be mounted on separate printed circuit boards which are electrically isolated from each other and adapted to be interconnected by means of connectors located along the respective dot-dash lines 516, 527 and 528. In any event, the components of the logic circuit 521a and analog circuit 521b

are preferably electrically isolated from each other. To that end, the logic circuit 501a preferably includes 5 V and ground leads from the mailing machine's power supply for providing the logic circuit 501a with a local 5 volt source 530 having 5 V and GND leads shunted by filter capacitors C1 and C2. And the analog circuit 501b includes 30 volt and ground return leads from the mailing machine's power supply for providing the analog circuit 501b with a local 30 volt source 536 including 30 V and GND leads shunted by filter capacitors C3 and C4. In addition, the analog circuit 501b includes a conventional 30 volt detection circuit 542 having its input conventionally connected to the analog circuit's 30 volt source 536, and its output coupled to a power up/down lead from the analog circuit via a conventional optical-electrical isolator circuit 544. Further, to provide the analog circuit 501b with a local 5 volt source 546, the analog circuit 501b is equipped with a conventional regulated power supply having its input appropriately connected to the analog circuit's 30 volt source 536 via a series connected resistor R1 and a 5 volt, voltage regulator 548. A zener diode D1, having its cathode shunted to ground and having its anode connected to the input of the 5 V regulator 548 and also connected via the resistor R1 to the 30 volt terminal line, is provided for maintaining the input to the 5 V regulator 548 at substantially a 5 volt level. In addition, a pair of capacitors C5 and C6 are provided across the output of the regulator 548 for filtration purposes.

To accommodate interfacing the postage meter's computer 41 (FIG. 1) with the computer 500, any two available ports of the computer 41 may be programmed for two-way serial communications purposes and coupled to the computer 500. For example, the postage meter's printing module 41c may be conventionally modified to include an additional two-way serial communications channel for communication with the computer 500.

Assuming the latter arrangement, serial input communications to the computer 500 (FIG. 22) are received from the postage meter computer's printing module 41c via the serial input lead to the logic circuit 501a (FIG. 22), which is operably coupled to port P3₀ of the microprocessor 502 by means of a conventional inverting buffer circuit 550. Accordingly, port P3₀ is preferably programmed for serial input communications, and the input to the buffer circuit 550 is resistively coupled to the logic circuit's 5 volt source 530 via a conventional pull-up resistor R2. Serial output communications from the microprocessor 502 are transmitted from port P3₁. Accordingly, port P3₁ is preferably programmed for serial output communications, and is operably coupled to the input of a conventional inverting buffer 552, the output of which is resistively coupled to the logic circuit's 5 V source 530 via a suitable pull-up resistor R2 and is additionally electrically connected to the serial output lead from the logic circuit 501a.

Since it is preferable that the microprocessor 502 be reset in response to energization of the logic circuit 501a, the logic circuit's 5 V source 530 is connected in series with an R-C delay circuit and a conventional inverting buffer circuit 554 to the reset pin, RST, of the microprocessor 502. The R-C circuit includes a suitable resistor R3 which is connected in series with the logic circuit's local 5 V source 530 and a suitable capacitor C7 which has one end connected between the resistor R3 and the input to the buffer circuit 554, and the other end connected to the logic circuit's ground return.

In addition to the VCC and GND (i.e., VSS) terminals of the microprocessor 502 being respectively conventionally connected to the logic circuit's 5 volt source and ground, since the microprocessor 502 does not utilize an external program memory, the $\bar{EA}$ terminal is connected to the logic circuit's 5 V source. And, in addition to the program storage enable and address latch enable terminals, PSEN and ALE not being used, the $\bar{EA}$ terminal is available for future expansion, as are ports P_{23} and P_{26-7} , and the read and write terminals, RD/ P_{37} and WR/ P_{36} , and one of the interrupt terminals INTO/ P_{32} .

In general, the microprocessor 502 is programmed for receiving input data from the postage meter drum's home position encoder 82, each of the M.Incr. and M.Decr. keys 53c and 53d, the envelope sensors 56, 58 and the D.C. motor shaft encoder 126, and, in response to a conventional communication from the postage meter's printing module 41c, timely energizing the D.C. motor under the control of the CPU of the microprocessor 502. Ports P_{20} and P_{21} , respectively receive transition signals, via the lines M.Incr. and M.Decr. from the keys 53c and 53d to permit the microprocessor to generate a running up and down count summation of the total number of depressions of each of the keys 53c and 53d. The current count summation is stored in an available working buffer of the microprocessor 500 and, in addition, is stored in an available buffer of a non-volatile memory NVM 500a (FIG. 22a-1). As shown in FIG. 22a-1, the NVM 500a is conventionally coupled to the microprocessor 500, for example, by means of an interface circuit which comprises three eight-bit shift registers 500b, 500c and 500d. The register 500b, which functions as a parallel to serial signal converter, receives data in parallel from the NVM ports I/O₀₋₇, and serially transfers the same to the microprocessor's port P₁₅ via the output port Q₄ of the register 500b. The register 500c, which functions as a serial to parallel signal converter, receives data signals serially from port P₁₅ of the microprocessor 500 via the serial input port SER and transfers same in eight-bit parallel signal format to ports I/O₀₋₇ of the NVM 500a. And for addressing the NVM 500a, the register 500d, which functions as a serial to parallel signal converter, receives address signals in serial form from port P₁₆ of the microprocessor 500 and transfers the same in eight-bit parallel signal format to the address ports A₀₋₇ of the NVM 500a. As shown in FIG. 22a-1 the registers 500b, 500c and 500d, and the NVM 500a, are respectively conventionally coupled to the microprocessor 500, utilizing microprocessor ports P₂₂ and P₁₇ respectively for address and data clock purposes, ports P₂₄ and P₂₅ respectively for read and write enablement control purposes, and ports P₁₆ and P₁₅ respectively for address and data signal communication purposes. Port P₀ is programmed for receiving a transition signal representative of the disposition of the postage meter's drum 38 at its home position; transition signals from the envelope sensors 56 and 58 which represent detection of the leading edge of a mailpiece or other sheet 16 being fed to the drum 38 to permit calculation by the computer 500 of the velocity of the mailpiece and thus the desired angular displacement of the D.C. motor shaft 122 and thus the drum 38; and a count representative of the actual angular displacement of the D.C. motor shaft 122. Preferably, port P₀ is multiplexed to alternately receive inputs from groups of the various sensors, under the control of an output signal from Port P₃₄ of the microprocessor 502. The shaft encoder 82

which is utilized for sensing the home position of the postage meter drum 38 is coupled to the computer 500 via the drum home position lead of the logic circuit, which, in turn, is connected to one input of a differential amplifier 562, the output of which is connected to the other input of the differential amplifier 562 via a feedback resistor R₄. The aforesaid other input to the amplifier 562 is also resistively coupled, by means of a resistor R₅, to the midpoint of a voltage divider circuit including resistors R₆ and R₇. Resistors R₆ and R₇ are connected in series with each other and across the logic circuit's 5 V source and ground return leads. The LED sensors 56 and 58, which are utilized for successively sensing the leading edges of each envelope being fed by the letter transport, are separately coupled to the computer 500 via the envelope sensor-1 and envelope sensor-2 input leads of the logic circuit 501a. In the logic circuit 501a, the envelope sensor-1 and sensor-2 leads are connected on a one-for-one basis to one of the inputs 15 of a pair of conventional amplifiers 564, the other inputs of which are connected together and to the mid-point of a voltage divider including resistors R₈ and R₉. Resistors R₈ and R₉ are connected in series with each other and across the logic circuit's 5 V source and ground return leads. Further, the three output signals from the differential amplifier 562 and the two amplifiers 564 are connected on a one-for-one basis to the three input ports P₀₋₂ of the microprocessor 502, each via a conventional tri-state buffer circuit 566, one of which is shown. The 20 input signals A and B from the D.C. motor shaft encoder 126 are coupled to the logic circuit 501a by means of leads A and B, which are conventionally electrically connected to the counting circuit 270 to provide the microprocessor 502 the count representative of the 25 actual angular displacement of the motor shaft 122 from its home position. The counting circuit's leads Q_{0-Q7} are electrically connected on a one-for-one basis to Ports P_{0-P7} of the microcomputer 502 via one of eight conventional tri-state buffer circuits 568, one of 30 which is shown, having their respective control input leads connected to each other and to the output of a conventional inverting buffer circuit 570, which has its input conventionally connected port P₃₄ of the microprocessor 502. Thus, either the three input signals, i.e., 35 from the drum home position and the two envelope position sensors are operably electrically coupled to Ports P_{0-P2} of the microprocessor 502, or the eight input signals Q_{0-Q7} from the counter circuit 270 are operably electrically coupled to ports P_{0-P7} of the 40 microprocessor 502, for scanning purposes, in response to an appropriate control signal being applied to the respective buffer circuits 566 and 568 from port P₃₄ of the microprocessor 502. In operation, assuming a low logic level signal is required for activating either of the 45 sets of buffers 566 or 568; when the microprocessor 502 applies such a signal to port P₃₄, the buffer circuits 566 operate, whereas since the buffer circuit 570 inverts this signal to a high logic level signal before applying the same to the buffer circuit 568, the latter is inoperative. 50 Conversely, a high logic level signal from port P₃₄ will operate buffer circuits 568 and not operate the buffer circuits 566. Accordingly, depending upon the level, high or low, of the signal from port P₃₄ of the microprocessor 502, the eight bit input to one or the other buffer circuits 566 or 568 will be made available to port P₀ for scanning purposes. Aside from the foregoing, to 55 permit the microprocessor 502 to clear the counter 270 for any reason in the course of execution of the program.

gram, port P3₅ is connected to the clear pin CLR of the counter 270 via a conventional inverting buffer 572, and the microprocessor 502 is programmed for timely applying the appropriate signal to port P3₅ which, when inverted, causes the counting circuit 270 to be cleared.

In general, ports P1₀-P1₃ are utilized by the microprocessor 502 for providing pulse width modulated (PWM) motor control signals for controlling energization of the D.C. motor 120 and port P1₄ is utilized by the microprocessor 502 for controlling energization of the solid state, A.C. motor, relay 52 and thus operation of the mailpiece conveyor 49. To that end, ports P1₀-P1₄ of the microprocessor 502 are each conventionally electrically connected on a one-for-one basis to the input of a conventional inverting buffer circuit 580, one of which is shown. The outputs of each of the buffer circuits 580 are connected on a one-for-one basis, via a conventional resistor R10, to output leads from the logic circuit 501_b, one of which is designated solid state, A.C. motor, relay, and four of which are respectively designated T1, T3, T2 and T4, since, as shown in FIG. 7, the four preamplifier stages of the power amplifier utilized for driving the D.C. motor 120 include the transistors T1-T4. Thus, the upper nibble of the signal from port P1 is utilized for controlling energization of the D.C. motor and one bit of the lower nibble is utilized for controlling energization of the solid state, A.C. motor, relay 52 and thus the A.C. motor 50. In the analog circuit 501_b, each of the leads T1, T2, T3, T4 and solid state relay, from the logic circuit 501_a, is electrically connected on a one-for-one basis to the anode of the light emitting diode D1 of five, conventional, photo-transistor type, optical-electrical isolator circuits 303. Since the cathodes of the light emitting diodes D1 of the opto-isolator circuits 303 are connected to each other and to the 5 volt lead from the analog circuit 501_b which extends to the 5 volt source of the logic circuit 501_a, the motor control signals are isolated from the power system of the analog circuit 501_b to avoid having spurious noise signals in the analog circuit 501_b and its components interfere with the control signals generated by the microprocessor 502. The analog circuit 501_b also includes a lead, designated power up/down, which extends from the analog circuit 501_b to the logic circuit 501_a and is connected to the microprocessor's interrupt INTI, port P3₃, to provide the microprocessor 502 with an appropriate input signal when the power is turned on, off or fails. In the analog circuit 501_b, the power up/down lead from the logic circuit 501_a is coupled to the thirty volt detect circuit 542 by means of a conventional optoisolator 544, the power up/down lead being electrically connected to ground through collector-emitter circuit of the opto-isolator's photo-transistor when the light emitting diode D1 is lit in response to the D.C. supply voltage level matching the internal reference voltage level, e.g., 30 volts, of the 30 volt detection circuit.

In the analog circuit 501_b each of the outputs from the photo-transistors of each of the opto-isolators 303 are resistively coupled to the analog circuits 5 V source by means of a conventional pull-up resistor 305, and the emitters of the photo-transistors T5 are connected to the analog circuit's ground system. In addition, the collectors of the photodiodes of the opto-isolators 303, which are utilized for transmitting the motor control signals from ports P1₀-P1₃ of the microprocessor 502 are connected on a one-for-one basis to the appropriate input leads A, B, C and D of the power amplifiers

shown in FIG. 7, the outputs of which are connected to the D.C. motor 120. Further, the collector of the photodiode of the opto-isolator 303 which is utilized for transmitting the A.C. relay control signals from port P1₄ of the microprocessor 502 is connected to the input lead of a conventional darlington-type power amplifier 550, the output of which is conventionally connected to the mailing machine's 30 volt D.C. source via a solid state, A.C. motor, relay 52, which is in turn conventionally connected for energizing the A.C. motor 50 from the local A.C. source.

In general, the computer 500 includes three software programs, including a main line program FIG. 23, a transmit and receive program and a command execution program, respectively identified by the 600, 700 and 800 series of numbers. When the mailing machine 10 is energized by actuation of the main power switch 24, the resulting low level logic signal from D.C. supply is applied to the reset terminal RST of the computer's microprocessor 502, thereby enabling the microprocessor 502. Whereupon, as shown in FIG. 23, the microprocessor 502 commences execution of the main line program 600.

The main line program 600 (FIG. 23) commences with the step of conventionally initializing the microprocessor 602, which generally includes establishing the initial voltage levels at the microprocessor's ports, and interrupts, and setting the timers and counters. Thereafter, the D.C. motor drive unit is initialized 604. Step 604 entails scanning the motor home position sensor input port P0₀, to determine whether or not the D.C. motor 120 is located in its home position and, if it is not, driving the motor 120 to its home position. Assuming the D.C. motor 120 is in its home position, either before or after the initialization step 604, the program then enters an idle loop routine 606.

In the idle loop routine 606, a determination is initially made as to whether or not the sampling time period of $T=1$ millisecond has elapsed, step 608, it being noted that each successive sample is taken at the time instant T_n immediately after and in response to the fourth 250 millisecond interrupt generated by the timer utilized for implementing the sampling time period T. Assuming the time period T has not elapsed, the program loops to idle 606. On the other hand, assuming the time period T has elapsed, the microprocessor 502 updates the servo-control system, step 610. For the purpose of explaining step 610 it will be assumed until otherwise stated that the desired location of the postage meter drum 38, and thus the motor drive shaft 122, is the home position. Step 610 includes the successive steps 610_a and 610_b, respectively, of sampling the count of the actual position P_a of the motor drive shaft 122 at the sampling time instant T_n , and fetching the previously computed count representing the desired position P_d of the shaft 122 at the same sampling time instant T_n . If for any reason the motor drive shaft 122 is not located in its home position when the value of the desired position count $P_d(T_n)$ is representative of the home position location, then the values of $P_a(T_n)$ and $P_d(T_n)$ will be different. On the other hand, if the motor drive shaft 122 is located in its home position when the desired position count $P_d(T_n)$ is representative of the home position location, then the values of $P_a(T_n)$ and $P_d(T_n)$ will be the same. Accordingly, computation of the error count, 610_c, may or may not result in an error count value $E(T_n)$ of zero. Further, independently of the computed value of $E(T_n)$, the computed value $G(T_n)$ of the motor

control signal, step 601d, may or may not result in a value of $G(T_n)$ of zero; it being noted that although step 610c results in a computed value of $E(T_n)=0$, the value of g_2 may not be equal to zero due to the computed value of the error for the next previous sampling time instant $E(T_{n-1})$ having resulted in a non-zero value, step 610g. Assuming steps 610c and 610d both result in zero value computations, then, upon updating and generating the PWM motor control signal, step 610e, no motor control signal will be generated. Under any other circumstances, step 610e will result in generating a PWM motor control signal for driving the D.C. motor 120, and thus the drum 38, to its home position. Thereafter, as shown in step 610f, the computed values of $E(T_n)$ and $G(T_n)$ are utilized as the values of $E(T_{n-1})$ and $G(T_{n-1})$ respectively for pre-calculating the value of g_2 for the next subsequent time instant T_n .

Accordingly, the computation made in the next step, 610g, to obtain the value of g_2 for the next sampling time instant T_n is made by utilizing the replacement values $E(T_{n-1})$ and $G(T_{n-1})$. Thereafter, as shown in step 610h, the desired position count P_d for the next sampling time instant T_n is made, which, as previously stated has been assumed to be representative of location of the motor drive shaft 122 in its home position. At this juncture it should be noted that the next step 612 in the program is to determine whether or not the enable flag is set, and, as hereinafter further discussed, this inquiry will be answered in the negative, causing the program to return to idle 606, unless a command has been received from the postage meter's computer 41 which results in feeding a mailpiece 16 to the postage meter drum 38. Accordingly, until a mailpiece 16 is fed to the postage meter drum 38, the main line program will continuously loop through steps 608, 610 and 612. As a result the motor drive shaft 122, and thus the drum 38, will be driven to the home position, against any force tending to move the drum 38 or shaft 122 out of the home position, until a mailpiece 16 is fed to the drum 38.

At this juncture it will be assumed that the enable flag is set, as a result of which the inquiry of step 612 is answered affirmatively, or, as above stated, a mailpiece 16 is being fed to the drum 38. Accordingly, the microprocessor 502 commences polling the ports connected to the envelope sensors 56 and 58, step 614. Since polling occurs at one millisecond time intervals, the polling sequence is continuous. As shown by the following step 616, between successive time instants T_n , the program continuously loops to idle 606 and through steps 608-616 inclusive until the envelope sensing sequence for a given envelope is complete. Whereupon the microprocessor commences executing step 618, which includes the steps of calculating the envelope's velocity, 618a; then fetching from memory the corresponding acceleration, deceleration and constant velocity constants, 618b; for computation of the desired position counts P_d at each successive time instant T_n in advance of sampling the actual position counts P_a as hereinbefore discussed in connection with step 610; then fetching the time delay t_d corresponding to the particular velocity V_1 for commencing acceleration of the drum 38 to the target velocity V_1 , step 618c; then fetching the count representative of the summation n of the number of depressions of the marginal increase and decrease keys 53c and 53d for adjusting the value of the time delay t_d to the total calculated time delay t_{pd} based upon operator input, and implementing the total time delay value t_{pd} for establishing the changed marginal distance

the indicia is to be spaced from the leading edge of the sheet when printed, 618d; and then commencing drum rotation by generating the desired position P_d for the initial one millisecond sampling time instant of acceleration of the motor drive shaft 122 and storing the value for subsequent use in step 601b. Accordingly, the value of P_d will no longer be assumed to be the value representative of the home position.

Thereafter the inquiry is made as to whether or not the drum cycle is complete, step 620. Assuming as stated above that only the initial desired value of P_d has been computed and stored, this inquiry of step 620 will be answered in the negative. Whereupon the microprocessor 502 transmits a status message, step 622, to the postage meter's computer 41 and the program loops to idle 606. Thereafter the microprocessor 502 continuously executes steps 608-620 until the entire P_d count sequence 618d for the trapezoidal-shaped velocity versus time profile for the target velocity V_1 has been exhausted. In this connection it is noted that the drum cycle T_{cl} is not complete until the settling time interval T_s which is allowed for damping any overshoot of the motor drive shaft 122 is complete. During the settling time interval T_s the value of P_d is a constant and representative of the home position of the shaft 122 and thus the drum 38. Assuming that the drum cycle is complete, the inquiry of step 620 will be answered affirmatively. Whereupon the microprocessor 502 transmits a status message, step 624, to the postage meter's computer 41 and the program loops to idle 606. Thereafter, the foregoing steps 606-622 of the main line, servo-control, idle loop are continuously executed by the microprocessor 502 in accordance with the above discussion until the main power switch 24 is opened by the operator.

The serial communications program 700 includes the transmit status routine 704. The latter routine 704 includes the steps of receiving and decoding any message, step 706, and invoking the execute command routine, step 708, both of which steps are self explanatory.

Assuming the execute command routine 800 has been invoked, step 708, the microprocessor 502 executes the routine 800 commencing with the step 802 of inquiring whether or not the decoded message is an enable command. Assuming the answer is yes, an enable status flag is set, step 804, to indicate that an envelope is to be fed to the drum 38. Whereupon the A.C. motor relay 52 is energized, step 806, for feeding the envelope to the drum 38, and the transmit status routine is invoked, step 808. On the other hand, assuming the decoded message is not an enable command, step 802, an enable status flag is cleared, step 810. Whereupon the A.C. relay is deenergized, step 812, and the status transmit routine is invoked 808.

Assuming the status transmit routine 702 has been invoked, step 806, the microprocessor 502 executes the routine 702 commencing with the step 710 of inquiring whether or not the drum cycle is complete. Assuming completion of the drum cycle, a drum cycle complete message is transmitted to the postage meter's computer 41, step 712. On the other hand, assuming the drum cycle is not complete, an inquiry is made as to whether or not the A.C. relay is energized, step 716, and, if it is, an A.C. relay energized message is transmitted to the postage meter's computer 41, step 718. If however the drum cycle is not complete, step 710, and the A.C. relay is not energized, step 716, then, an A.C. relay deenergized message is transmitted to the postage meter's computer 41, step 720. Upon transmitting any of the

messages, drum cycle complete, step 710, A.C. relay energized, step 716, or A.C. relay deenergized, step 720, the microprocessor 502 returns to the idle 606 of the main line program 600.

The term postage meter as used herein includes any device for affixing a value or other indicia on a sheet or sheet-like material for governmental or private carrier parcel, envelope or package delivery, or other purposes. For example, private parcel or freight services purchase and employ postage meters for providing unit value pricing on tape for application on individual parcels.

A more detailed description of the programs herein-

before discussed is disclosed in the appended program listing which describes in greater detail the various routines incorporated in, and used in the operation of, the postage meter.

Although the invention disclosed herein has been described with reference to a simple embodiment thereof, variations and modifications may be made therein by persons skilled in the art without departing from the spirit and scope of the invention. Accordingly, it is intended that the following claims cover the disclosed invention and such variations and modifications thereof as fall within the true spirit and scope of the invention.

What is claimed is:

- Sheet handling apparatus comprising:
  - means for feeding a sheet in a predetermined path of travel, the sheet having a reference edge;
  - means for sensing the reference edge of the sheet in the path of travel and providing at least one sensing signal indicative of the velocity thereof;
  - rotary printing means for printing postage indicia on the sheet; and
  - means for controlling the printing means, the sensing means coupled to the controlling means, the controlling means including microcomputer means constructed and arranged to be energized from a local source of supply of power, the microcom-

55

puter means including means responsive to said at least one sensing signal for providing a time delay before commencement of operation of the printing means, the microcomputer means including means for controlling the angular velocity of the printing means in consideration of sampled increments of angular velocity thereof to cause the postage indicia to be printed on the sheet a predetermined marginal distance from the reference edge of the sheet, the controlling means including keyboard means coupled to the microcomputer means, the keyboard means including at least one key selectively operable for generating at least one key signal representative of a desired change in the marginal

distance, the microcomputer means including means responsive to said key signal for providing an adjusted time delay before commencement of operation of the printing means whereby the printing means is controlled to cause the postage indicia to be printed on the sheet a changed marginal distance from the reference edge of the sheet, the changed marginal distance including the predetermined distance changed by the desired change in the marginal distance, and the microcomputer means including non-volatile memory means for storing therein an amount representative of the desired change in marginal distance when the microcomputer means is de-energized.

2. The apparatus according to claim 1, wherein the at least one key includes a key selectively depressible for generating the least one key signal, and the at least one key signal representing at least one increment of increase in the predetermined marginal distance.

3. The apparatus according to claim 1, wherein the at least one key includes a key selectively depressible for generating the at least one key signal, and the at least one key signal representing at least one increment of decrease in the predetermined marginal distance.

4. The apparatus according to claim 1, wherein the at least one key includes two keys, each of said two keys being selectively depressible, one of said two keys generating in response to each depression thereof a first signal representative of an increment of increase in the predetermined marginal distance, and the other of said two keys generating in response to each depression thereof a second signal representative of an increment of decrease in the predetermined marginal distance.

5. The apparatus according to claim 4, wherein the microcomputer means includes means for generating a summation count of said first and second signals, said count being representative of the desired change in the marginal distance.

6. The apparatus according to claim 5, wherein the microcomputer means includes means for storing a first amount representative of an increment of distance, and the microcomputer means including means for generating a second amount representative of the product of the summation count and the increment of distance, said second amount being representative of the desired change in the marginal distance.

7. The apparatus according to claim 5, wherein the nonvolatile memory means includes means for storing an amount representative of the summation count.

8. Sheet handling apparatus comprising:

- a. means for feeding a sheet in a predetermined path of travel;
- b. means for sensing the sheet in the path of travel and providing at least one sensing signal indicative of the velocity thereof;

c. rotary printing means for printing postage indicia on the sheet; and
d. means for controlling the printing means, the sensing means coupled to the controlling means, the controlling means including microcomputer means, the microcomputer means including means responsive to said at least one sensing signal for providing a time delay before commencement of operation of the printing means, the microcomputer means including means for controlling the angular velocity of the printing means in consideration of sampled increments of the angular velocity thereof to cause the postage indicia to be printed on the sheet a predetermined marginal distance from a reference edge of the sheet, the controlling means including keyboard means coupled to the microcomputer means, the keyboard means including at least one key selectively operable for generating at least one key signal representative of a desired change in the marginal distance, the microcomputer means including means responsive to said key signal for providing an adjusted time delay before commencement of operation of the printing means whereby the printing means is controlled to cause the postage indicia to be printed on the sheet a changed marginal distance from the reference edge of the sheet, the changed marginal distance including the predetermined distance changed by the desired change in marginal distance, and the microcomputer means including nonvolatile memory means for storing therein an amount representative of the desired change in marginal distance.

9. The apparatus according to claim 8, wherein the at least one key includes two keys, each of said two keys being selectively depressible, one of said two keys generating in response to each depression thereof a signal representative of an increment of increase in the marginal distance, and the other of said two keys being depressible for generating a signal representative of an increment of decreases in marginal distance, and the microcomputer means including means responsive to the key signals for generating a summation count of said signals, said count being representative of the net total of the increments of increase and decrease, and said count being said amount representative of the desired change in marginal distance.

10. The apparatus according to claim 8, wherein the means for providing the time delay in response to the sensing signal includes means for fetching a predetermined time delay.

11. The apparatus according to claim 8, wherein the means for providing the adjusted time delay includes means for calculating the adjusted time delay.
